Primary Examiner — Brandon M Rosati*Assistant Examiner* — Janice Lim(74) *Attorney, Agent, or Firm* — Plumsea Law Group, LLC(57) **CLAIM**

The ornamental design for a loudspeaker, as shown and described.

DESCRIPTION

FIG. 1 is a perspective view of embodiment one, of a loudspeaker, showing our new design;

FIG. 2 is a front elevational view thereof;

FIG. 3 is a side elevational view thereof;

FIG. 4 is a top plan view thereof;

FIG. 5 is a perspective view of embodiment two, of a loudspeaker, showing our new design;

FIG. 6 is a front elevational view thereof;

FIG. 7 is a side elevational view thereof; and,

FIG. 8 is a top plan view thereof.

The broken line portions show unclaimed subject matter only and form no part of the claimed design. The dot-dash broken line portions are included to show the boundary between the claimed portion and unclaimed portion only and form no part of the claimed design.
